Primary Examiner — Katherine A Holbrow

(57) **CLAIM**

The ornamental design for a display screen with graphical user interface, as shown and described.

DESCRIPTION

The FIGURE is a front view of a display screen with graphical user interface, showing the new design.

The outer perimeter broken lines showing a device illustrate environmental structure and form no part of the claimed design. The inner perimeter broken lines show a display screen and form no part of the claimed design. All broken lines within the display screen show portions of a graphical user interface and form no part of the claimed design.
